UNITED STATES PATENT OFFICE

JOHN E. JIMMIS, OF WAUKAU, WISCONSIN

PUMP OPERATING MECHANISM

Application filed April 25, 1931. Serial No. 532,769.

This invention relates to improvements in pump operating mechanism.

One of the objects of the present invention is the provision of an improved type of operating mechanism for pumps in order to increase the leverage, so that the pumps which are used on deep wells, or high pressure systems, can be operated with less effort than the usual type of operating mechanism.

Another object of the present invention is the provision of an improved type of pump operating mechanism which can be quickly and readily placed in position and operatively connected with the pitman of the pump and manually controlled for operating deep well pumps and the like, with means for increasing or decreasing the stroke of the pitman.

A further object of the present invention is the provision of pump operating mechanism of the above type which includes a rack bar connected with the pitman and cooperating with a manually controlled gear segment, together with means for engaging the gear segment with the rack or readily disengaging the same therefrom.

With the above and other objects in view, the invention consists in the novel features of construction, the combination and arrangement of parts hereinafter more fully set forth, pointed out in the claims and shown in the accompanying drawing wherein:

Figure 1 is a side elevation illustrating the application of my improved pump operating mechanism;

Figure 2 is a detailed section on the line 2-2 of Figure 1;

Figure 3 is a detailed transverse section on the line 3-3 of Figure 4; and

Figure 4 is detailed side elevation illustrating a form of the invention with improved means for moving the gear segment into and out of engagement with the rack bar.

Referring to the drawing, it will be noted that I have illustrated an ordinary type of pump, the body of which is generally indicated at 1. Cooperating with the pump body and mounted for reciprocating movement therein is a pitman 2. Attached to the upper end of the body 1, is a bracket 3 which

comprises two opposed members each having one end arranged upon opposite sides of the upper end of the pump body and clamped thereto by means of the bolts 4. The other ends of the opposed members of the bracket 3 have attached thereto, the spaced upright struts 5 and connected to the upper ends of the struts 5 is a guide arm 6 adapted to embrace the upper end of the pitman for guiding the same in its movement, and carrying a bearing roller 7 engaging the pitman to permit the same to ride freely through the outer end of the arm 6.

Attached to the pitman 2 is a rack bar 8 having a plurality of spaced teeth 9 cooperating with the teeth 10 on the gear segment 11.

The gear segment 11 is pivotally mounted between the struts 5 and is supported by means of a pivot bolt 12. Formed integral with the body of the gear segment 11 is a lateral projecting arm 13 having spaced ears 14 at the outer end, said ears being apertured to receive the pin 15 which detachably connects the upper end of the link 16 to the outer end of the arm 13.

Arranged between the lower end of the struts 5 and positioned between the outer end of the opposed members of the bracket 3 is the apertured head 17 of the hand lever 18. The head 17 is pivotally mounted upon a collar 19 supported by the pivot bolt 20 which is also used for connecting the lower ends of the struts 5 to the bracket 3.

The handle 18 is provided with an arcuate curved portion 21 which has a transverse opening 22 to receive the lower end of the link 16. The lower end of link 16 is pivotally connected to the arcuate portion of the handle by means of the pin 23.

It will be apparent from the above construction, that by connecting the handle member 18 with the pitman 2, through the medium of the gear segment 11 and the rack bar 8, it will not require as much leverage as would be ordinarily required if the handle was connected direct to the pitman, and by adjusting the upper end of the link 16 in the spaced ears 14, the leverage can be lengthened or shortened as required.

It will be noted that the spaced ears 14 at

the outer end of arm 13 are provided with spaced apertures, so that the outer end of link 16 can be connected to either set of the apertures for adjusting the movement of the 5 arms 13.

In Figures 3 and 4, I have illustrated a slightly modified form of the invention wherein the gear segment 11 has its body portion provided with a central opening 24 in which is arranged a cam roller 25, keyed to the cross shaft 26, the ends of which are mounted in the spaced struts 5'. One end of the shaft 26 has attached thereto a crank arm 27, carrying a lateral projecting handle 28, whereby the cam roller 25 may be manually rotated for moving the gear segment 11' into engagement with the rack carried by the pitman or disengaging the same therefrom.

In the main form of the invention, the hand 20 lever 18 may be quickly and easily disconnected from the gear segment 11 by removing either pin 15 or pin 23, so that the direct connection between the hand lever and the gear segment will be broken. It will also be 25 noted that with this type of operating mechanism, the usual required leverage for operating the pitman 2 is considerably reduced, so that comparatively heavy pumps can be manually actuated with comparative ease.

30 The device is simple in construction and can be manufactured and applied to various types of pumps at a very low price, but will prove very efficient for the purpose intended.

While I have shown and described the preferred embodiment of my invention, it will be apparent from the foregoing that slight changes may be made in the construction when putting the invention into practice without departing from the spirit of the same 40 or the scope of the appended claims.

I claim:

1. In a pump, the combination with a pump casing and a pump rod, of operating means for the pump comprising a support including spaced upper and lower arms and a connecting vertical upright, means connecting the lower arm to the pump casing, means carried by the upper arm for slidably receiving the pump rod, a rack bar secured to the pump rod between the arms, a sector gear rockably mounted on the upright engaging the rack bar, said sector gear having an outwardly extending arm, an operating lever pivotally secured to the lower end of the upright, and a link pivotally connected to the lever and to the arm of the sector gear.

2. In a pump, the combination with a pump casing and a pump rod, of operating means for the pump comprising a support including upper and lower arms and a connecting vertical upright, a clamp carried by the lower arm engaging the casing, a guide carried by the upper arm receiving the pump rod, a rack bar carried by the pump rod intermediate the arms, a cam rotatably carried by the upright

intermediate its ends, a sector gear rockably mounted on the cam engaging the rack bar, an outwardly extending operating arm on the sector gear, a hand lever rockably mounted on the upright, a link operatively connecting the operating arm with the hand lever, and means including a hand crank for rotating said cam.

In testimony that I claim the foregoing I have hereunto set my hand at Omro, in the 75 county of Winnebago and State of Wisconsin.

JOHN E. JIMMIS.
